Attorneys.

UNITED STATES PATENT OFFICE

JOHN A. HANWAY, OF DETROIT, MICHIGAN, ASSIGNOR TO WAGNER SIGN SERVICE INC., OF CHICAGO, ILLINOIS, A CORPORATION OF ILLINOIS

ELECTRIC SIGN

Application filed February 13, 1931. Serial No. 515,499.

My invention relates to improvements in electric signs and has for one object to provide a new and improved type of electric sign wherein letters of the sign may be selectively and interchangeably illuminated from behind or may be picked out by light units projecting forwardly from the front of the sign. In general, my invention relates to luminous electric signs which comprise a box or housing, the outer wall of which carries a plurality of letter panels, the letter being formed by openings through the panel. Back of the panel and closing the opening is normally a translucent colored plate or ray filter and inside the housing is a source of light. My invention contemplates substituting for the translucent panel or ray filter an opaque panel which may be placed behind the letter panel and which will have in its surface a plurality of electric light sockets extending rearwardly, these sockets registering with the letter opening so that after the panel has been placed, an electric light source, for instance, a plurality of bulbs or one or more neon tubes may be mounted on the opaque panel in the letter opening projecting forwardly from the plane of the sign so as to pick out or emphasize individual letters in the sign by the use of individual especially conspicuous light bulbs which give both a special illuminating effect and which result in the production of a sign in three dimensions instead of two dimensions as is usually the case with luminous signs. Other objects will appear from time to time throughout the specification and claim.

My invention is illustrated more or less diagrammatically in the accompanying drawings, wherein—

Figure 1 is a side elevation of a luminous sign;

Figure 2 is a section along the line 2—2 of Figure 1;

Figure 3 is a section along the line 2—2 of Figure 1 showing my interchangeable panel in place.

Like parts are indicated by like characters throughout the specification and drawings.

A is a main frame or housing. It has a side wall comprising a plurality of panels

A¹ through which are cut letter apertures A². Back of each panel are a plurality of guide tracks A³. In these tracks are slidably mounted translucent color panels or ray filters A⁴ of glass or other suitable material. 55 Mounted within the housing are a plurality of light sources A⁵ which may take the form of electric light bulbs of any desired character. When the light is turned on, the light from these bulbs is seen through the translucent panels and through the letter openings, thus giving a luminous sign. This luminous sign is all in the plane of the wall of the housing and is made up of a plurality of two dimension characters or letters illuminated from behind. 60 65

When it is desired to change the character of these letters so as to emphasize individual letters or individual words in the sign, selected translucent panels are withdrawn and an opaque panel B is slid into place behind the letter to replace the translucent panel or ray filter. This opaque panel is made of metal or other suitable material having sufficient rigidity and may be colored as desired 70 to form a satisfactory reflecting surface for the letter. B¹ B² are a plurality of electric light sockets mounted on the back of the opaque panel and projecting into the interior of the housing. They are provided with electric conductors B² of any desired type whereby the sockets may be energized. It will be noted that the sockets are flush with the front plane of the opaque panel so that the panel may be slid into place just as the glass or translucent panel was and so that there will be no interference with the positioning of the opaque panel. Also this panel may lie immediately against the letter panel and will thus entirely close the letter opening. Electric light bulbs B³ are socketed in the panel through the front so that they project forwardly in the third dimension in front of the plane of the letters, thus giving an individually illuminated three dimension letter. 75 80 85 90 95 When it is desired to remove this letter the electric light bulbs are screwed out, thus making it possible for the opaque panel to be withdrawn.

While I have illustrated the device with 100

the conventional type of screw base electric light bulbs, obviously other types may be used and instead of a plurality of electric light bulbs spaced to outline the letter, a 5 single light source, for instance, a neon tube might be used socketed on the opaque panel.

Either a glass plate or an opaque plate is slid in a position from above along the guide tracks or channels A³. Joining the lower 10 ends of the guide tracks or channels A³ are transverse channels A¹⁸ shown in dotted lines on Figure 1 and in full lines in elevation from the outside on Figures 2 and 3. Thus when in place the plate or channel is held on 15 both sides and the bottom.

I claim:

An illuminated sign comprising a housing having an apertured wall, a supporting means within the housing adjacent the wall, 20 an opaque panel movable edgewise along the wall into and out of register with the aperture therein, an electric light socket projecting rearwardly from the panel, an electric light source removably seated in the socket and 25 projecting outwardly through and located in front of the aperture in the wall.

Signed at Detroit, County of Wayne and State of Michigan, this 26th day of January, 1931.
